UNITED STATES PATENT OFFICE.

AUGUSTUS WOLF, OF CHAMBERSBURG, PENNSYLVANIA.

MIDDLING-MILL.

1,344,470.

Specification of Letters Patent. Patented June 22, 1920.

Application filed July 1, 1919. Serial No. 307,970.

To all whom it may concern:

Be it known that I, AUGUSTUS WOLF, a citizen of the United States, residing in Chambersburg, Franklin county, Pennsylvania, have invented certain Improvements in Middlings-Mills, of which the following is a specification.

My invention relates to machinery employed in the manufacture of flour; and one object of my invention is to provide an improved form of mill for the purpose of extracting from that form of bran known as "middlings" all of the available flour contained therein. In the usual practice of milling, the "middlings" contain considerable flour that fails to separate therefrom in any of the sifting operations, and at the same time is too slight to be crushed by the rolls.

20 To secure this flour, I propose to employ mechanism designed to impart a squeezing pressure to the middlings; my improved means serving to force the middlings against a surface in a thin stream under such pressure as to insure substantially complete crushing of the middlings and the flour accompanying the same to a fineness that will permit of the substantially complete recovery of the flour from the feed.

30 My invention also includes special means for regulating the pressure upon the floury middlings at the point of emergence from the squeezing means, and means for quickly releasing the pressure applying parts in order to relieve any strain caused by the pressure of foreign material that may have become jammed therein.

40 A further object of my invention is to provide a mill in which the floury and fibrous matter of the middlings passed therethrough may be more quickly and satisfactorily separated and in such a manner that the flour produced from the reduced middlings is improved in color.

45 A further object of my invention is to provide means for additionally crushing the fine middlings at the squeezing point, and a still further object is to provide means for securing endwise adjustment of the feed screw to insure proper crushing or squeezing of the middlings at all times.

These and other features of my invention are more fully described hereinafter, reference being had to the accompanying drawings, in which:

Figure 1, is a side elevation of a mid-

dlings mill embodying the improvements forming the subject of my invention.

Fig. 2, is an end elevation of the same.

Fig. 3, is a longitudinal section on the line III—III, Fig. 2.

Fig. 4, is a section on the line IV—IV, Fig. 3.

Fig. 5, is an end view of the plate against which the middlings are squeezed, and

Fig. 6, is a sectional view on the line VI—VI, Fig. 1.

As illustrated in the accompanying drawings, my present structure may comprise a cylindrical casing 1, having a feed hopper 70 or receiving throat 2, at one end, and a discharge outlet or throat 3, at the opposite end. The throat 3 may communicate with a delivery chamber 4, whereby the crushed middlings may be delivered to reels or 75 sieves, and the shell or casing providing the chamber 4 may also serve as a supporting base for the structure.

Disposed within the casing 1 is a screw having a body 5 of substantially the same 80 diameter throughout and tapering at the forward end as at 6, and having a pair of threads 7 which may have portions 7^a differing slightly in diameter from portions 7^b of the same; the part 1^a of the chamber of 85 the casing directly beneath the feed hopper 2, being slightly smaller in diameter than the greater portion of the chamber formed by such casing; a construction facilitating the feeding of the middlings to the squeezing point. While I have shown the threads of the screw as double, it will be understood that triple or any other convenient number of threads may be employed, without departing from the scope of my invention. 95

The end of the cylindrical casing 1 through which the middlings are forced by the screw is preferably cut off squarely at right angles to its axis as indicated at 8, and abuts the beveled edge portion 10 of a plate 100 11 situated outside and yieldingly held in contact with said end; such plate being disposed in the throat chamber 3 at the front end of the casing through which the recovered flour drops, and from which it may 105 pass to sieves, or any suitable form of separator. The inner surface of the plate 11 is provided with angularly disposed teeth or projections 12 inwardly of its beveled edge, whose duty and function it is to effect a 110 crushing action upon the middlings fed between the same and the end of the screw

and its threads. For the purpose of yieldingly holding such plate 11 against the end 8 of the casing, elongated bolts 15 are provided, which are connected to lugs 16 projecting outwardly from said plate; being held thereto by nuts 17, and said bolts extend rearwardly for operative connection with a collar 18 encircling the casing. The ends of said bolts are provided with thumb nuts 19, having springs 20 between the same and the collar 18, so that a yielding connection is provided, permitting release of the parts should any foreign matter accompany the middlings and be caught at the point 15 where the squeezing operation occurs—between the end of the cylinder or the screw and the plate 11 against which the middlings are crushed or squeezed.

The collar 18 is provided with cam faces 21 against which the springs 20 engage; such springs occupying the highest position with respect to said cams when the structure is in the operative position, and washers may be disposed at the ends of the springs. 25 Should any foreign substance be present in the middlings and be brought by the screw to the point of extrusion and catch there, the plate 11 can be quickly relieved by imparting rotative movement to the collar 18 30 by a handle 22, which will cause the cams to ride beneath the springs, thereby releasing the tension of the same and releasing the pressure applied to the plate 11, so as to relieve any material caught thereby, or 35 permit removal of the same.

Pressure is applied to the plate 11 through the springs 20 on the bolts 15, and a nut 23 carried by the casing and contacting with the ring or collar 18, is employed to increase 40 or decrease this pressure; the casing being threaded at 24 for movement of the nut thereon. The nut may be provided with lugs 25 whereby it may be readily turned, and upon turning said nut, tension of the 45 springs can be increased or decreased, thereby increasing or decreasing the pressure holding the plate 11 against the end of the cylinder, and regulating the amount of pressure applied to the material extruded between the end of such cylinder and said 50 plate.

The screw is preferably mounted in suitable bearings 26 and 27 at the ends of the machine, which may be of any suitable type 55 desired. Between the rear end of the screw and the end 28 of the casing, which end 28 may be in the form of a cap member threaded in place, I provide adjusting means for keeping the forward end of the screw adjacent and substantially in crushing contact 60 with the plate 11. These adjusting means may comprise a member 30 having arms 31 laterally disposed, and a single arm 32 vertically disposed, as clearly shown in Fig. 6. 65 A screw 33 externally applied is adapted to

a notch or slot 34 in the arm 32 of this member so as to maintain the latter in proper relative position with respect to the screw, while screws 35, with lock nuts 36, are in engagement with the arms 31 and serve to 70 adjust the member 30 against the rear end of the feed screw whereby its forward end may be held in contact with the plate 11. The body 5 of the screw may be held to the shaft 37 by a set screw 37^a, and the shaft is 75 preferably provided with an elongated seat 38 permitting adjustment of said screw on the shaft to take up any wear at the end adjacent the plate 11, being maintained in such adjusted position by the plate 30 and 80 the means backing or supporting the same.

The structure may be driven by providing the shaft with a pulley 40, whereby power may be applied thereto, or it can be driven by hand. Access to the outlet throat 3 may 85 be provided by a door 41, and access to the chamber 4 may be provided by a door 42.

The ends of a plurality of the bolts 15 may be steadied by passing the same through lugs or bosses 15^a carried by the 90 casing of the feed hopper 2.

I claim:

1. The combination of a casing, a screw operating therein, means for driving the screw, and a movable plate forming a closure for one end of the casing; said plate having a smooth wall with which the end of the cylinder engages and between which parts material within the cylinder may be extruded upon turning the screw and a 100 toothed or serrated surface against which the material may be crushed by the end of the screw.

2. The combination of a casing, a screw operating therein, means for driving the 105 screw, a movable plate forming a closure for one end of the casing; said plate having a smooth wall with which the end of the cylinder engages and between which parts material within the cylinder may be ex- 110 truded upon turning the screw and a toothed or serrated surface against which the material may be crushed by the end of the screw, and means for yieldingly supporting said plate.

3. The combination of a cylindrical casing having a smooth inner surface, a screw operating therein, means for driving the screw, a movable plate forming a closure for one end of the casing; said closure plate 120 having a smooth wall engaging the end of the cylinder between which parts material within the cylinder may be extruded upon turning the screw and a toothed or serrated surface against which the material may be 125 crushed by the end of the screw, and means for adjusting said screw to maintain it in substantial contact with said plate.

4. The combination of a cylindrical casing having a smooth inner surface, a screw 130

operating therein, means for driving the screw, a movable plate forming a closure for one end of the casing; said closure plate having a smooth wall engaging the end of the cylinder between which parts material within the cylinder may be extruded upon turning the screw and a toothed or serrated surface against which the material may be crushed by the end of the screw, 5 means for yieldingly holding said plate to the end of the cylinder, and means for adjusting said screw endwise to maintain it in substantial contact with the plate.

5. The combination of a cylindrical casing having a smooth inner surface, a screw operating therein, means for driving the screw, a movable plate forming a closure for one end of the casing; said closure plate having a smooth annular beveled edge 10 engaging the end of the cylinder between which parts material within the cylinder may be extruded upon turning the screw and a toothed or serrated surface against which the material may be crushed by the end of the screw, a plate at the rear end of said screw, and means for moving said plate to keep the screw in operative contact with the closure plate at the end of the casing.

6. The combination of a cylindrical casing having a smooth inner surface, a screw operating therein, means for driving the screw, a movable plate forming a closure for one end of the casing; said closure plate having a smooth annular beveled wall 15 engaging the end of the cylinder between which parts material within the cylinder may be extruded upon turning the screw and a toothed or serrated surface against which the material may be crushed by the end of the screw, a plate at the rear end of said screw, means for moving said plate to keep the screw in operative contact with the closure plate at the end of the casing, and adjustable yielding means for holding said 20 closure plate against the end of the cylinder.

7. The combination of a cylindrical casing, a plate having a beveled edge yieldingly held against the end of said casing, a screw for moving granular material against said plate whereby it may be extruded in an annular stream, a series of bolts supporting said plate in position, springs on said bolts for applying tension to said plate, 25 a cam-carrying sleeve surrounding the casing through which said bolts pass; said springs being disposed between said cam sleeve and thumb-nuts on the ends of the bolts, a nut for increasing or decreasing 30 said tension; said nut being threaded on the

cylinder and in contact with the sleeve, and cams on said sleeve for permitting longitudinal movement of said bolts to relieve the tension of said springs when said cam sleeve is turned.

8. The combination of a cylindrical casing, a plate having a beveled edge yieldingly held against the end of said casing, a screw for moving granular material against said plate whereby it may be extruded from the casing in an annular stream, a series of bolts supporting said plate in position, a cam-carrying sleeve through which the bolts pass, springs on said bolts and interposed between said sleeve and thumb-nuts for applying tension to said plate, a nut for increasing or decreasing said tension; said nut being threaded on the casing in contact with said sleeve and being disposed between the sleeve and the plate, 45 and cams on said sleeve permitting longitudinal movement of said bolts to relieve the tension of said springs when said cam sleeve is turned.

9. The combination of a casing, a screw operating therein, means for driving the screw, and a movable plate forming a closure for one end of the casing; said plate having a toothed or serrated surface against which the material may be crushed by the 50 end of the screw and an annular smooth surface surrounding said serrated surface adapted to discharge the crushed material.

10. The combination of a casing, a screw operating therein, means for driving the screw, a movable plate forming a closure for one end of the casing; said plate having a toothed or serrated surface against which the material may be crushed by the end of the screw and an annular smooth surface 55 surrounding said serrated surface adapted to discharge the crushed material, and means for yieldingly supporting said plate.

11. The combination of a casing, a screw operating therein having a plurality of threads; said threads having one diameter at one end of the screw and another diameter at the opposite end thereof and the casing being of such a size as to accommodate the different sized portions of said 60 screw threads, and a movable plate forming a closure for one end of the casing; said plate having a toothed or serrated surface against which the material may be crushed by the end of the screw and another surface 65 in contact with the end of the casing serving to additionally crush the material and between which and the plate such material is extruded.

AUGUSTUS WOLF.
